METHOD OF AND APPARATUS FOR RE-COVERING HEAT AND CHEMICALS

Leslie S. Wilcoxson, Ridgewood, N. J., assignor to
The Babcock & Wilcox Company, Jersey City,
N. J., a corporation of New Jersey

Application November 12, 1942, Serial No. 465,384

11 Claims. (Cl. 23—48)

1

The present invention relates in general to the recovery of chemicals and/or heat from waste liquor containing inorganic chemicals and combustible organic matter, and more particularly, to the recovery of chemicals and heat from the pulp digester residual liquor in the sulphate and soda processes of manufacturing pulp.

In the treatment of residual or "black" liquor from the pulp digesters used in the sulphate or "kraft" pulp industry, for example, the weak liquor from the digesters is usually concentrated to a solid concentration of 50-65% before delivery to the chemical recovery furnace. The inorganic chemical content of the liquor is mainly sodium carbonate (Na_2CO_3) and sodium sulphate (Na_2SO_4) together with traces of sodium sulphide (Na_2S) and other salts in various complex combinations with the lignuous matter. The heat values in the liquor are due to the presence of organic combustible matter or lignins released from the wood in the digesters.

The main functions of such recovery units are to recover the sodium salts in the form of smelt, reduce the sodium sulphate to sodium sulphide, and recover a high percentage of the heat values of the liquor in the form of steam. Such apparatus is well known and shown, for example, in my joint patent with G. H. Tomlinson No. 2,161,110. The reduction of the sulphate to sulphide is essential to permit its immediate reuse in the preparation of fresh cooking liquor for the digesters. This reducing action is usually represented as $Na_2SO_4 + 4C = Na_2S + 4CO$. With normal operation of such recovery units, about 92% of the available sulphate is reduced to the sulphide, and seldom more than 95%. It is believed that this reaction does not go to completion because some of the sulphide is reoxidized in the unit to sulphate.

A considerable amount of the chemical is evaporated, volatilized or sublimed under normal furnace temperature conditions, and even though subsequently solidified may be carried out of the unit with the products of combustion. The chemical losses due to unrecovered chemical may run from 50 to 150 pounds per ton of pulp. A large percentage of the volatile material is believed to be sodium sulphate formed by the union of volatilized sodium oxide with carbon dioxide, sulphur dioxide and oxygen in the heating gases in successive stages:

2

It is also believed that there is a critical temperature of about 2100° F. above which volatilization of such chemicals increases rapidly.

The volatilized or sublimed chemicals tend to 5 solidify on the heat absorbing surface of the unit as the temperature of the gases is reduced by heat absorption therefrom. Chemical particles are also present in the gases due to the suspension burning of spray particles. The deposited chemical 10 is usually found in substantially different conditions in the different parts of the unit, ranging from running smelt in the furnace to dry talc-like deposits in the boiler tube bank, depending upon the temperature conditions in the different portions of the unit. The chemicals tend 15 to adhere tightly to any surface on which they may deposit. When the surface on which the chemicals deposit are normally spaced convection heated steam boiler tubes, the depositing 20 chemicals tend to bridge over the intertube spaces and rapidly reduce the available gas flow area in that section with consequent disadvantageous results in the operation of the unit.

The general object of my invention is the provision 25 of an improved method of and apparatus for recovering chemicals and/or heat from waste liquors of the general character described. Further and more specific objects are the provision of an improved method of and apparatus 30 for incinerating pulp residual liquor in a self-sustaining manner and in which the percentage of reduction of the sodium sulphate to sulphide is increased, the volatilization and sublimation of the included chemicals is reduced, and the deposition of chemicals in a fused or semi-fused condition is confined to the furnace section of the unit. A further specific object is an improved construction and arrangement of the heat absorbing 35 surface in apparatus of the character described which provide a rapid solidification of any volatilized or sublimed chemicals in the furnace gases, which minimizes the deposition of chemicals and is readily cleaned by standard cleaning devices, and which facilitates the separation and recovery of chemicals in suspension 40 in the heating gases generated.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have ill-

lustrated and described a preferred embodiment of my invention.

In the drawings:

Fig. 1 is a sectional elevation of a high capacity chemical recovery unit constructed in accordance with my invention;

Fig. 2 is an enlarged view of the upper portion of Fig. 1;

Fig. 3 is a horizontal section taken on the line 3—3 of Fig. 2;

Fig. 4 is an enlarged view of the lower portion of Fig. 1 and taken on the line 4—4 of Fig. 5;

Fig. 5 is a vertical section taken on the line 5—5 of Fig. 4;

Fig. 6 is a plan view partly in section of one of the superheater tube supports;

Fig. 7 is an elevation partly in section on the line 7—7 of Fig. 6;

Fig. 8 is a view similar to Fig. 6 of a support at the opposite end of the superheater;

Fig. 9 is an elevation partly in section of the structure shown in Fig. 8;

Fig. 10 is an enlarged horizontal section taken on the line 10—10 of Fig. 2;

Fig. 11 is a front view of the structure shown in Fig. 10;

Fig. 12 is an enlarged view of the rear wall primary and secondary air connections;

Fig. 13 is a horizontal section showing the wind-box arrangement for the primary and secondary air systems; and

Fig. 14 is a side view of the wind-boxes shown in Fig. 13.

The chemical recovery unit illustrated in the drawings is particularly designed and especially useful for the treatment of residual liquor from the kraft or sulphate pulp process, and while capable of use over a wide range of capacities is particularly adapted for high capacity operation, such as, for example, incinerating the residual liquor from a pulp production of over 200 tons/day. The apparatus shown has a vertically elongated setting of substantially rectangular horizontal cross-section throughout and divided into a primary furnace section 10, a secondary furnace section 11, a steam superheating section 12, and a steam generating section 13, which are serially connected in the order named. The primary furnace section is defined by a front wall 15, a rear wall 16, side walls 17 and 18, and a rearwardly inclined bottom 19 forming a furnace chamber of substantially rectangular horizontal and vertical cross-section. All of the boundary walls are fluid cooled by rows of water tubes wholly or partly covered by refractory material, the front wall having a row of tubes 20 extending upwardly from a bottom header 21, the bottom and rear walls having a row of tubes 22 extending from the header 21 along the furnace bottom and thence upwardly along the rear wall, and the side walls 17 and 18 having tube rows 23 and 24 extending vertically from bottom headers 25 and 26 respectively. All of the described tubes are supplied with water through large diameter pipes 27 at opposite sides of the unit and pipe connections 28 leading therefrom to the headers 21, 25, and 26. The furnace bottom and lower sections of the rear and side walls are of the full studded type, i. e. these tubes are provided with metallic studs and the studs and tube surfaces completely covered with refractory to a level above the secondary air ports hereinafter described, providing a high percentage of refractory surface surrounding the fuel bed space. The front wall and upper portions of the side and rear walls are of the partial

stud type, i. e. the studs and refractory are confined to the intertube area, leaving a portion of the tubes exposed.

A continuously oscillating spray nozzle 30 of the character illustrated in said Patent No. 2,161,110, is positioned in the front wall intermediate the height of the primary furnace section and arranged to spray concentrated residual liquor across a large portion of the cross-sectional area of the furnace with the spray particles of a size and at a velocity sufficient to put the sprayed particles in a sticky condition when impacting on a vertical arresting surface formed by the side and rear walls, on which a major portion of the sprayed particles deposit. With this arrangement a mass of partly dried spray particles accumulates on the side and rear walls, as indicated in Figs. 4 and 5, and remains thereon until dried substantially completely by the rising gas stream passing over the surface thereof, forming a porous readily combustible char. The dried char falls in lumps from the walls onto the fuel bed in the furnace bottom, maintaining a fuel bed of substantial depth having the contours substantially as indicated in Figs. 4 and 5. One or more smelt outlets 31 are arranged in the front wall 15 at the lower end of the bottom 19.

In accordance with my invention air is supplied to the primary furnace chamber at three elevations therein in separately controllable primary, secondary and tertiary air streams. The provisions for supplying preheated primary and secondary air comprise a forced draft fan 32 having outlet control dampers 33 and a flue 34 incorporating a steam heated air heater 35. The flue 34 opens into a flue 36 extending along the rear side of the furnace, the flue 36 in turn being connected to wind boxes 37 along the side and rear walls. Each wind box 37 is divided by a horizontal partition 38 into an upper section 39 and a lower section 40. The lower section 40 of each wind box is subdivided by vertical partitions 41 and inclined horizontal partitions 42 to form a series of primary air compartments 40' with the air admission to each compartment 40' controlled by an externally operable inclined damper 43 positioned in a corresponding opening in the partition 42. Each compartment 40' opens to the primary furnace chamber 10 through vertically elongated rectangular primary air inlet ports 44 positioned in the side and rear walls between adjacent water tubes thereof and outwardly inclined. The air ports 44 are preferably arranged in a horizontal line along the rear wall and in rearwardly stepped groups along each of the side walls at a level relative to said walls at which the primary air ports will normally be submerged in the fuel bed. A supplementary control of each primary air port is supplied by an adjustable filler plate 45 at the outer end of each port and arranged to control the air velocity therethrough without changing the level of the bottom of the corresponding air stream.

The upper section 39 serves as a secondary air supply chamber extending the full length of each wind box. The chambers 39 receive their air supply from the duct 36 through branch conduits 47 at the rear corners of the furnace controlled by a series of secondary air dampers 48. The secondary air is delivered to the furnace chamber at a level slightly above the normal fuel bed level through a series of substantially horizontally arranged secondary air inlet ports 50. The ports 50 are in vertical alignment with some of the primary air ports 42 and of similar flow area but

only approximately half the number of primary air ports. Control of the individual secondary port areas is obtained by adjustable filler plates 51 adjustable to raise the effective bottom of the corresponding secondary air ports without changing the level of the top of the air stream therefrom.

The provisions for the tertiary air supply consist of an independently controlled fan 55 and discharge duct 56 leading to a rectangular windbox extending completely around the furnace chamber and opening thereto at a level above the upper char level through tertiary air inlet ports 58 in the front, rear and side walls similar in cross-section to the primary and secondary air ports and in alignment with alternate secondary air ports in the same wall. The ports 58 in the side walls 11, 18 are horizontally arranged and relatively staggered while those in the front and rear walls are on the same level but outwardly inclined and relatively staggered. Observation doors 59 are provided in the corresponding windboxes opposite each of the air ports 44, 50 and 58.

The secondary furnace section 11 forms a vertical continuation of the primary furnace chamber with its front and side walls defined by continuations of the walls 15, 17, and 18 respectively, and its rear side defined by a forwardly inclined partition or baffle 60 forming a continuation of the primary furnace rear wall 16 and arranged to progressively reduce the effective flow area of the lower part of the secondary furnace chamber. The baffle 60 is continued vertically to a point short of the rearwardly inclined roof 61 of the setting to form a rectangular opening 62 above the upper end of the baffle 60, while the tubes 22 extending along the furnace side of the baffle continue in a staggered arrangement across the opening 62 to a horizontal roof header 63. The front wall tubes 20 are continued along the roof 61 to the header 63, while the side wall tubes 23 and 24 continue upwardly to corresponding headers 64. The headers 64 are connected by tubes 65 to the steam space of the steam and water drum hereinafter described, and the header 63 by roof tubes 66. The portions of the front and side walls and roof in the secondary furnace chamber and the vertical section of the baffle 60 are preferably constructed to provide a greater amount of metallic heat absorption area than the wall portions in the primary furnace chamber, and in this section the tube studs are replaced by stud plates 66 lining the exposed intertube areas, as shown in Figs. 6 and 7.

As shown in Figs. 2 and 3, the secondary furnace chamber contains a series of laterally spaced vertical tube platens, each formed by spaced parallel tubes 67 extending inwardly from vertical headers 68 beyond the front wall 15, and thence vertically the entire height of the secondary furnace chamber. Their upper ends are connected to corresponding horizontal headers 69 which are also connected to the steam space of the boiler drum by tubes 85. Four of such tube platens are shown in symmetrical arrangement relative to the center line of the secondary furnace chamber and provide a substantial amount of radiant and convection heated heat absorption area with a relatively low resistance to gas flow. The headers 68 are supplied by pipe connections 70 from the downcomer pipes 27.

The steam boiler section 13 constitutes the main convection heated steam generating section of the unit, and is located in the upper part of the setting rearwardly of and above the primary

furnace rear wall 16. The boiler section is of the two-drum vertical tube bank type and comprises an upper steam and water drum 71, a lower drum 72, a front tube bank 73, and a spaced rear tube bank 74. A tube baffle 75, formed by stud tubes and refractory as shown in Figs. 8 and 9, extends downwardly along the first row of boiler tubes 73 from the drum 71 to a point short of the lower drum 72, the space below the lower end of the baffle serving as a gas entrance to the space occupied by the tube bank 73. A second vertical baffle 76 extends upwardly from the drum 72 along the rear rows of the tube bank 73 to a point short of the upper drum 71, the space thereabove serving as a gas entrance into the space occupied by the tube bank 74. With this arrangement the heating gases delivered to the boiler section enter the lower end of the space occupied by the tube bank 73 and flow upwardly therethrough between the baffles 75 and 76 and over the upper end of the baffle 76 and downwardly along the tube bank 74 to the gas outlet flue 77 connected to the bottom of the setting. An economizer may be advantageously arranged in the gas outlet flue for the recovery of additional heat from the gases which can then be passed through a spray tower or disc evaporator to an induced draft fan and stack connection.

The steam superheater section 12 occupies the setting space between the baffle 60 and the boiler tube bank 73 with the upper end of the space opening to the screen passage 62 and its lower portion to the lower end of the tube bank space 73. The portion of that space immediately below the upper end of the baffle 60 is occupied by the steam superheating surface of the unit consisting of vertically spaced groups of superheater tubes 80 and 81 with corresponding tubes in each group serially connected. Each tube has vertically spaced horizontal leg portions connected by vertical loops which are expansibly supported on the tube baffles 60 and 75, as shown in Figs. 6-9. Each loop at one end carries a hollow hook-shaped lug 83 which extends over and rests on a pair of brackets 84 welded to adjacent tubes 22. At the opposite end each loop carries a hook-shaped lug 85 which fits over a pair of short bars 86 welded on the baffle tubes 73. Each superheater tube is positioned opposite to the intertube spaces of the corresponding supporting tubes 22 and 73, and the tube loops adjacent the baffle tubes 73 are arranged to project into the spaces between these tubes, the studs and refractory closing these intertube spaces to form the baffle 75 being arranged between the rear halves of the tubes.

Each superheater tube is connected to the steam space of the drum 71 by a riser tube 88 extending upwardly along the baffle 75 to the drum 71. The riser tubes 88 are positioned for most of their length between the adjacent tubes 73 so as to have their exposed faces substantially flush with the exposed faces of the tubes 73 and are held in that position by overlapping guide lugs 89 and 90 welded on the tubes 88 and 73 respectively, as shown in Figs. 10 and 11. This construction provides a relatively smooth surface along this portion of the baffle 75 which minimizes chemical deposits thereon and facilitates cleaning of the same while permitting relative expansion and contraction of the tubes 88 and 73.

The lowermost leg of the superheater tubes 81 is continued downwardly along the baffle 75 and across the entrance to the tube bank 73 to a hor-

izontal header 92 adjacent the drum 72 and from which the superheated steam is delivered to the point of use. The superheater tubes 80 and 81 occupy only a relatively small portion of the superheater section 12, leaving a substantial cavity therein both above and below the superheater tubes. The upper unoccupied space serves as a gas turning space for the gases passing through the screened opening 62, while the lower cavity affords a substantial space for the separation of dry chemical solids in suspension in the gases, while facilitating the turning of the gases into the tube bank space 73. The inclined smooth rear side of the baffle 60 forms the front wall of a hopper 93 at the bottom of the superheater section and receives the solids separating in the superheater section and also from the tube bank space 73. The opposite side of the hopper is formed by a wall 94 extending downwardly at an angle from the drum 72 across the header 92 to a point in alignment with the rear wall 16. The wall 94 is continued downwardly and rearwardly from that point to form an outlet 95 for the hopper which is connected to one or more pipes 96 leading to suitable mechanical injectors 97 for discharging the collected solids through the rear wall of the primary furnace section onto the fuel bed.

The described apparatus is particularly effective for treating sulphate pulp residual waste liquor in accordance with my improved process of incineration. According to my invention in normal operation the weak black liquor from the pulp digesters is concentrated in multiple effect evaporators to a concentration of approximately 50% solids. The liquor concentration is subsequently increased in a spray tower or disc evaporator to about 60-62% solids. Following this point the make-up chemical or salt cake is mixed with the liquor in a mixing tank and the liquor subsequently heated to a temperature of approximately 220° F. The concentrated liquor is then pumped to the spray nozzle 30 whereby it is sprayed onto the side and rear walls of the primary furnace as previously described. The sprayed liquor is partly dried and some of the volatile constituents distilled off during its passage across the furnace chamber in intimate contact with the uprising gas stream. The particles after being deposited on the walls are almost completely dried and most of the remaining volatiles distilled off, by contact with the rising gas stream, thus forming a porous char which falls to the fuel bed from time to time in irregular lumps. The combustible organic content of the char is burned on the furnace bottom under a controlled reducing atmosphere, some of the heat generated being utilized in the smelting of the chemicals and the reduction of the sodium sulphate to sodium sulphide before the discharge of the smelt through the smelt outlet 31 to a suitable dissolving tank.

In the operation of known recovery units of this general type a total combustion air supply of approximately 125% of the theoretical amount of air required for complete combustion of the heat values of the liquor is divided between vertically spaced sets of primary and secondary air ports with the primary air ports above a relatively shallow fuel bed and arranged to discharge high velocity air streams sweeping over the fuel bed surface at spaced points. This impingement of the primary air streams tends to produce localized temperatures in the adjacent parts of the fuel bed considerably above the critical volatili-

zation temperature of 2100° F., increasing volatilization and sublimation of chemicals in these portions of the fuel bed.

In accordance with my invention the localized combustion of exposed portions of a relatively shallow fuel bed is replaced to a large extent by a submerged combustion over a substantial part of a relatively deep fuel bed, such as is used in gas producers. The more uniform and lower combustion temperatures resulting in the bed advantageously reduce the amount of chemicals volatilized or sublimed therein. The amount of primary air supplied for this purpose is reduced and distributed more widely in the fuel bed. The primary air velocity is made as low as possible to minimize the amount of solids carried upwardly into the gas space of the furnace chamber by the gaseous products of combustion, yet is maintained sufficient to secure the desired penetration of the fuel bed and to keep the primary air ports clear of char and smelt. By way of example and not of limitation, between 85% and 90% of the theoretical amount of combustion air required can be supplied to the primary air ports at a static pressure of 4 to 5 in. H₂O, providing a velocity at the air inlet ports of 8-10,000 feet per minute. Due to the submergence and number of the primary air ports the primary air is brought intimately in contact with a large portion of the fuel bed. This distributed and submerged arrangement of the primary air ports provides combustion of the fuel bed over a large area and maintenance of the smelted chemicals under reducing conditions until discharged, so that little or none of the sulphide produced is reoxidized to the sulphate. The amount of chemicals passing upwardly into the gas space of the unit is also reduced due to the substantial filter action of the superjacent portions of the fuel bed.

The secondary air supply is regulated to provide combustion of the combustible volatiles distilled from the bed and carbon monoxide produced to produce sufficient heat to dry the char on the walls and partly dry the sprayed liquor traveling across the furnace chamber. From 10-15% of the theoretical air requirements is supplied through the secondary air ports. The static pressure maintained at the secondary air ports can be less than that at the primary air ports, as for example, of the order of 1-2 in. H₂O resulting in a secondary air entrance velocity of 1-3,000 feet per minute. The primary and secondary air are preferably preheated to a temperature of 280°-350° F. to promote ignition in the fuel bed and high temperature conditions around the center portion of the bed.

About 12% excess air is supplied through the tertiary air ports at a high velocity, windbox static pressures of 10 to 12 in. H₂O and entrance velocities of 15,000-18,000 feet per minute being preferred. The tertiary air supply is intended to complete the combustion of the free carbon, carbon monoxide and hydrocarbons in the gases at a level above the char level of the furnace. The high velocity tertiary air streams in the staggered and angularly spaced arrangement described promote mixing and turbulence in the rising gases and insure intimate contact of the air and combustible constituents of the furnace gases as to insure rapid and complete combustion. Elimination of solids from the gases is also facilitated by the large gas flow area and consequently low gas velocities in the primary furnace section.

The rising gases then enter the high heat ab-

sorption zone formed by the completely water cooled secondary furnace chamber. The progressive reduction of the effective flow area in this section offsets the cooling of the gases and increases the convection heating effect on the tube platens. Solidification of the chemicals in the gases is rapidly effected in the secondary furnace section and a substantial amount of chemicals collect on the furnace walls and tube platens and are returned to the primary furnace section by gravity alone or the periodic cleaning operations. The heating gases continue their upward flow and turn through the screened opening 62, the screen tubes providing a substantial amount of convection heating surface. The remaining chemicals in suspension are ordinarily in a solid condition on entering the superheater section. The substantial increase in gas flow area in the superheater section due to the cavities therein and the two major changes in direction of gas flow therein are effective in separating most of the remaining solids in the gases. The separated solids collect in the hopper 93 and are returned to the primary furnace chamber by the injector. The vertical arrangement of the boiler tubes and the parallel flow of the heating gases relative thereto minimize the collection of chemicals on the tube surfaces and permit the same to be readily cleaned with mechanical soot blowers.

While in accordance with the provisions of the statutes I have illustrated and described herein the best form of my invention now known to me, those skilled in the art will understand that changes may be made in the form of the apparatus and operation of the process disclosed without departing from the spirit of the invention covered by my claims, and that certain features of my invention may sometimes be used to advantage without a corresponding use of other features.

I claim:

1. The process of recovering chemicals and heat from liquor containing inorganic chemicals and combustible matter which comprises spraying the liquor into a vertical furnace chamber in intimate contact with an ascending stream of high temperature gases, collecting dehydrated combustible material to form a fuel bed of substantial depth in the bottom of the furnace chamber, and supplying combustion air to said furnace chamber so as to minimize chemical carryover therefrom comprising supplying a major portion of the total air supply but less than the theoretical air requirements as primary combustion air in a series of spaced streams directly to submerged portions of the fuel bed for self-sustaining combustion of the combustible material and smelting of the included inorganic chemicals therein under reducing conditions, supplying secondary combustion air in an amount not more than the balance of the theoretical combustion air requirements and in a series of spaced streams directly to the space between the fuel bed and the spray level for the combustion of combustible gases rising from the fuel bed, independently controlling the amount and velocity of the primary and secondary air streams to maintain a maximum temperature in the fuel bed sufficient to smelt the included inorganic chemicals therein but normally below 2100° F. and supplying the remaining air as tertiary combustion air in a series of spaced streams directly to the portion of the furnace chamber above the

spray level for the combustion of combustible gases present above the spray level.

2. The process of recovering chemicals and heat from liquor containing inorganic chemicals and combustible matter which comprises introducing the liquor into a vertical furnace chamber in a spray directed across the furnace chamber and formed of spray particles of a size and at a velocity such that a major portion of the spray particles impact on an arresting surface after passing through and being heated by an ascending stream of high temperature gases sufficiently to put the spray particles when impacting in a sticky condition, maintaining the sticky particles in an adhering mass on the arresting surface until sufficiently dehydrated to separate and form a fuel bed of combustible material of substantial depth in the bottom of the furnace chamber, and supplying combustion air to said furnace chamber so as to minimize chemical carryover therefrom comprising supplying a major portion of the total air supply but less than the theoretical air requirements as primary combustion air directly to submerged portions of the fuel bed for the combustion of the combustible material and smelting of the included inorganic chemicals therein under reducing conditions, supplying secondary combustion air directly to the space between the fuel bed and the spray level for the combustion of combustible gases rising from the fuel bed, and supplying tertiary combustion air directly to the portion of the furnace chamber above the spray level for the combustion of combustible gases present above the spray level.

3. The process of recovering chemicals and heat from liquor containing inorganic chemicals and combustible matter which comprises introducing the liquor at a solid concentration in the range of approximately 50-65% solids into a vertical furnace chamber in a spray directed across the furnace chamber and formed of spray particles of a size and at a velocity such that a major portion of the spray particles impact on an arresting surface after passing through and being heated by an ascending stream of high temperature gases sufficiently to put the spray particles when impacting in a sticky condition, maintaining the sticky particles in an adhering mass on the arresting surface until sufficiently dehydrated to separate and form a fuel bed of combustible material of substantial depth in the bottom of the furnace chamber, and supplying combustion air to said furnace chamber so as to minimize chemical carryover therefrom comprising supplying a major portion of the total air supply but less than the theoretical air requirements as primary combustion air in a series of spaced streams directly to submerged portions of the fuel bed for the combustion of the combustible material and smelting of the included inorganic chemicals therein under reducing conditions, controlling the amount of and velocity of the primary combustion air to maintain a maximum temperature in the fuel bed sufficient to smelt the included inorganic chemicals therein but normally below 2100° F., supplying secondary combustion air in a series of spaced streams directly to the space between the fuel bed and the spray level for the combustion of combustible gases rising from the fuel bed, and supplying tertiary combustion air in a series of spaced streams directly to the portion of the furnace chamber above the spray level for the combustion of combustible gases present above the spray level.

4. The process of recovering chemicals and heat from liquor containing inorganic chemicals and combustible matter which comprises introducing the liquor at a solid concentration in the range of approximately 50-65% solids into a vertical furnace chamber in a spray directed across the furnace chamber and formed of spray particles of a size and at a velocity such that a major portion of the spray particles impact on an arresting surface after passing through and being heated by an ascending stream of high temperature gases sufficiently to put the spray particles when impacting in a sticky condition, maintaining the sticky particles in an adhering mass on the arresting surface until sufficiently dehydrated to separate and form a fuel bed of combustible material of substantial depth in the bottom of the furnace chamber, and supplying combustion air to said furnace chamber so as to minimize chemical carryover therefrom comprising supplying a major portion of the total air supply but less than the theoretical air requirements as primary combustion air in a series of horizontally spaced streams directly to submerged portions of the fuel bed for the combustion of the combustible material and smelting of the included inorganic chemicals therein under reducing conditions, controlling the amount of and velocity of primary combustion air to maintain a maximum temperature in the fuel bed sufficient to smelt the included inorganic chemicals therein but normally below 2100° F., supplying secondary combustion air in an amount approximating the balance of the theoretical air requirements and in a series of horizontally spaced streams directly to the space between the fuel bed and the spray level for the combustion of combustible gases rising from the fuel bed, and supplying the remaining air as tertiary combustion air in a series of horizontally spaced streams at a velocity substantially higher than the velocity of the primary air streams directly to the portion of the furnace chamber above the spray level for the combustion of combustible gases present above the spray level.

5. The process of recovering chemicals and heat from liquor containing inorganic chemicals and combustible organic matter which comprises introducing the liquor at a solid concentration in the range of approximately 50-65% solids into a vertical furnace chamber in a spray directed across the furnace chamber and formed of spray particles of a size and at a velocity such that a major portion of the spray particles impact on an arresting surface after passing through and being heated by an ascending stream of high temperature gases sufficiently to put the spray particles when impacting in a sticky condition, maintaining the sticky particles in an adhering mass on the arresting surface until sufficiently dehydrated to separate and form a fuel bed of combustible material of substantial depth in the bottom of the furnace, introducing primary air directly to submerged portions of the fuel bed, introducing secondary air directly to the space between the fuel bed and the spray level, introducing tertiary air directly to the portion of the furnace chamber above the spray level, passing the heating gases generated upwardly through a zone of high heat absorption at an increased velocity to reduce the gas temperature sufficiently to solidify sublimed chemicals therein, directing the heating gases downwardly at a low velocity through a solid separating zone, and returning the chemical solids

separated in the separating zone directly to the fuel bed.

6. The process of recovering chemicals and heat from liquor containing inorganic chemicals and combustible organic matter which comprises introducing the liquor at a solid concentration in the range of approximately 50-65% solids into a vertical furnace chamber in a spray directed into the furnace chamber in intimate contact with an ascending stream of high temperature gases, collecting dehydrated combustible material to form a fuel bed of substantial depth in the bottom of the furnace chamber, introducing primary air in a series of distributed streams directly to submerged portions of the fuel bed, introducing secondary air at a relatively low velocity directly to the space between the fuel bed and the spray level, introducing tertiary air in a series of streams and at a velocity substantially higher than the primary air velocity directly to the portion of the furnace chamber above the spray level, passing the heating gases generated upwardly through a zone of high heat absorption at an increased velocity to reduce the gas temperature sufficiently to solidify sublimed chemicals therein, directing the heating gases downwardly at a low velocity through a solid separating and steam superheating zone, returning the chemical solids separated in the separating zone to the fuel bed, and then directing the heating gases vertically through a steam generating zone.

7. Apparatus for recovering chemicals and heat from liquor containing chemicals and combustible organic matter comprising vertical front, rear and side walls defining a stationary furnace chamber of the vertical shaft type of substantially rectangular horizontal cross-section having an upper section and a communicating lower section, spray means in said front wall for introducing liquor so arranged that the liquor is directed in an expanding spray substantially horizontally across said upper section so that the sprays impact against at least one of the remaining vertical walls over an extended area, a hearth at the bottom of said lower section arranged to receive substantially dry material falling from said last mentioned wall to form a fuel bed therein, means for supplying air to said furnace chamber including a series of primary air inlet ports in said lower section side walls opening to said furnace chamber at a level below the normal upper level of said fuel bed, a series of secondary air inlet ports in said lower section side walls opening to said furnace chamber at a level between the normal upper level of said fuel bed and said spray level, and a series of tertiary air inlet ports in said upper section side walls opening to said furnace chamber above said spray level, a gas outlet from said upper section wholly above the spray level, and an outlet in said lower section for the combustible residue.

8. Apparatus for recovering chemicals and heat from liquor containing chemicals and combustible organic matter comprising vertical walls defining a stationary furnace chamber of the vertical shaft type having an upper section and a communicating lower section, spray means in one of said vertical walls for introducing liquor so arranged that the liquor is directed in an expanding spray across said upper section so that the spray impacts against an arresting surface in said upper section, a hearth at the bottom of said lower section arranged to receive the substantially dry material falling from said arresting surface to form a fuel bed thereon, means for supplying air

to said furnace chamber including a series of horizontally spaced primary air inlet ports in said lower section walls opening to said furnace chamber at a level below the normal upper level of said fuel bed, a series of horizontally spaced secondary air inlet ports in said lower section walls opening to said furnace chamber at a level between the normal upper level of said fuel bed and said spray level, said secondary air inlet ports being substantially less in number and more widely spaced apart than said primary air inlet ports, and a series of horizontally spaced tertiary air inlet ports in said upper section walls opening to said furnace chamber above said spray level, said tertiary air inlet ports being substantially less in number and more widely spaced apart than said secondary air inlet ports, a gas outlet from said upper section wholly above the spray level, and an outlet in said lower section for the incombustible residue.

9. Apparatus for recovering chemicals and heat from liquor containing inorganic chemicals and combustible organic matter comprising vertical walls forming a setting including a vertical furnace chamber, spray nozzle means extending through one of said vertical walls and constructed and arranged to spray liquor, in an expanding spray, into said furnace chamber, a hearth at the bottom of said furnace chamber arranged to receive combustible residue to form a fuel bed on said hearth, means for supplying air to said furnace chamber, a vertically extending partition wall arranged to divide the upper part of said setting into a vertical gas upflow pass forming a continuation of said furnace chamber and an adjoining vertical downflow pass, laterally spaced vertically extending platens of steam generating tubes arranged in said upflow pass, steam superheater tubes extending across said downflow pass, and a steam generating tube bank positioned at one side of and arranged to receive heating gases from said downflow pass.

10. Apparatus for recovering chemicals and heat from liquor containing inorganic chemicals and combustible organic matter comprising vertical walls forming a setting including a vertical furnace chamber, spray nozzle means extending through one of said vertical walls and constructed and arranged to spray liquor, in an expanding spray, into said furnace chamber, a hearth at the bottom of said furnace chamber arranged to receive combustible residue to form a fuel bed on said hearth, means for supplying air to said furnace chamber including a series of primary air inlet ports in said vertical walls opening to said furnace chamber at a level below the normal upper level of said fuel bed, a series of secondary air ports in said vertical walls opening to said furnace chamber at a level between the normal upper level of said fuel bed and the level of said spray nozzle means, a series of tertiary air inlet ports in said vertical walls opening to said furnace chamber at a level above the level of said spray nozzle means, a vertically extending partition wall arranged to divide the upper part of said setting into a vertical gas upflow pass forming a continuation of said furnace chamber

and an adjoining vertical gas downflow pass, steam superheater tubes extending across said downflow pass and arranged transversely of the gas flow therein, and a steam generating tube bank positioned at one side of and arranged to receive heating gases from said downflow pass.

11. Apparatus for recovering chemicals and heat from liquor containing inorganic chemicals and combustible organic matter comprising vertical walls forming a setting including a vertical furnace chamber, spray nozzle means extending through one of said vertical walls and constructed and arranged to spray liquor, in an expanding spray, into said furnace chamber, a hearth at the bottom of said furnace chamber arranged to receive combustible residue to form a fuel bed on said hearth, means for supplying air to said furnace chamber including a series of primary air inlet ports in said vertical walls opening to said furnace chamber at a level below the normal upper level of said fuel bed, a series of secondary air ports in said vertical walls opening to said furnace chamber at a level between the normal upper level of said fuel bed and the level of said spray nozzle means, a series of tertiary air inlet ports in said vertical walls opening to said furnace chamber at a level above the level of said spray nozzle means, a vertically extending partition wall arranged to divide the upper part of said setting into a vertical gas upflow pass forming a continuation of said furnace chamber of reduced flow area and an adjoining vertical gas downflow pass, laterally spaced vertically extending platens of steam generating tubes symmetrically arranged in said upflow pass, steam superheater tubes extending across said downflow pass, a hopper forming the bottom of said downflow pass, means for returning material collecting in said hopper to said fuel bed, and a steam generating tube bank positioned at one side of and arranged to receive heating gases from said downflow pass.

LESLIE S. WILCOXSON.
